(57) **CLAIM**

We claim the ornamental design for a film dispensing tool for stationery, as shown and described.

DESCRIPTION

FIG. 1 is a left side view of the film dispensing tool for stationery, showing our new design, with the dispensing tip in a storage position;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a perspective view thereof;

FIG. 8 is a perspective view of the film dispensing tool for stationery of FIG. 1, with the dispensing tip extended for use;

FIG. 9 is a left side view thereof;

FIG. 10 is a right side view thereof;

FIG. 11 is a top view thereof;

FIG. 12 is a bottom view thereof;

FIG. 13 is a front view thereof;

FIG. 14 is rear view thereof; and,

FIG. 15 is another perspective view of the film dispensing tool for stationery shown in FIG. 8, with the transparent portions of the tool casing shown in gray.

The broken lines shown in FIG. 1 form no part of the claimed design.
